UNITED STATES PATENT OFFICE

CARL ZETTERLUND, OF CHICAGO, ILLINOIS

HOISTING APPARATUS

Application filed November 5, 1928. Serial No. 317,170.

My invention relates broadly to hoists for elevating machines used particularly for elevating building material and similar objects to higher levels, say in the construction of buildings, and has particular reference to a machine of this type which is automatic in the operation of stopping the elevator platforms when reaching a predetermined level.

An object of the invention is to provide a machine of the above mentioned general character whereby two or more elevator platforms will be alternately raised and lowered by suitable power apparatus, to desired levels, and will there be automatically stopped.

15 A further object of the invention is to provide a structure wherein the mechanism for elevating the elevator platforms includes an improved type of reversing mechanism operable by manually actuated means at the unloading levels, whereby the elevator platforms will be alternately raised and lowered and the drive automatically disconnected or moved to neutral position when the ascending elevator platform reaches the unloading level.

25 Further objects and advantages of the invention will be apparent from the following detailed description when taken in connection with the accompanying drawings.

In the drawings:

30 Figure 1 is a side elevational view of a machine embodying the invention;

Fig. 2 is a top plan view of the same;

Fig. 3 is a transverse vertical sectional view taken on line 3—3 of Fig. 2;

35 Fig. 4 is a sectional view taken on the line 4—4 of Fig. 3; and,

Fig. 5 is a detail view of the driving connection.

Referring more particularly to the drawings wherein I have shown a preferred embodiment of the invention, any suitable base 10 may carry uprights or standards 11 which are connected at the top by a suitable cross member 12. These standards and necessary cross-connections provide a main supporting frame of conventional form, furnishing guides for the elevator platforms 14 and 15.

It will be understood that while only two of such platforms are illustrated, the mechanism herein disclosed may be adapted to

a hoist having any desirable number of platforms, depending upon the construction and type of hoist used. Supported by top cross member 12 are sheaves 16 and 17, about which the ends 18 and 19 of a cable are trained for connection to said platforms 14 and 15. This cable is adapted alternately to raise and lower the platforms and, as a consequence, when one end of the cable is being wound upon a drum 20, the other end is being released, which action results in the raising of one of the platforms and in the lowering of the other.

It is apparent from Figures 1 and 2 that both ends of the cable extend downwardly and under a double pulley 21, suitably supported upon or adjacent to base 10, from where said ends 18 and 19 of the cable are wound in the usual manner around drum 20.

The power for operating drum 20 and for providing alternate rotation to lower and raise platforms 14 and 15 is obtained through a reversing mechanism suitably carried upon platform 10. It will be understood that any suitable source of power may be employed to drive this reversing mechanism.

A bracket or suitable frame 21 may be mounted upon platform 10 and arranged with vertical standards 23 and 24 for supporting the drive and reversing mechanism. Bearings 25 and 26 are furnished in these standards to receive concentrically arranged driving sleeves 27 and 28. Sleeves 27 and 28 are disposed in bearing 26, each projecting to the right a predetermined distance to receive oppositely rotating drive gears 29 and 30.

These gears may be keyed or otherwise suitably fastened to the sleeves for driving the latter in opposite directions. The driving connection may comprise gear 31, meshing with outer gear 30, and also an intermediate gear 32, which is arranged to mesh with gear 29. It will be noted in Figure 5 that the gear ratios for the drive gears 29 and 30 are equal, whereby the sleeves 27 and 28 rotate in reverse directions at equal speeds. Sleeve 28 is relatively short and carries a clutch dog 33 thereon. Sleeve 27 extends crosswise and is received by the opposite frame bearing 25. Spaced at a fixed distance from clutch dog 163

33 is a second clutch dog 34 secured to sleeve 27. These clutch dogs 33 and 34, being secured to sleeves 27 and 28, respectively, rotate of course in opposite directions.

Referring to Figure 3, drum 20 is loosely mounted on sleeve 27 and is provided with a projection 35, to which is pivoted a clutch element 36 at 36'. Sleeve 27 is slotted at 37 to receive pin 38, whereby a collar 39 may be shifted along sleeve 27 and yet be rotatable therewith. This clutch collar 39 is grooved at 40 to receive clutch pins 41 carried by clutch element 36. Clutch element 36 is furnished with a finger 42 adapted to be swung alternately into and out of engagement with clutch dogs 33 and 34, when collar 39 is shifted along sleeve 27 to swing clutch element 36 about its pivotal mounting. Means for shifting clutch element 36 and collar 39 along sleeve 27 comprises a concentric shaft or rod 45 slidably arranged within sleeve 27 and projecting at the left-hand end thereof a suitable distance to receive a collar 46. Standard 23 may be furnished with frame extension 47, provided with oppositely extending ears 48 and 49, the ear 48 constituting a bearing for pin 50, which pin 50 is adapted to carry a clutch yoke 51 having studs 52 for riding in grooved collar 46. The upper end of shaft 50 is adapted to carry a segment 53 arranged to mesh with a gear 54 carried by a shaft 55 in frame extension 49.

A control or actuating device 60 having outwardly extending arms 61, 62, 63 and 64, is arranged as shown in Fig. 2, in a position relative to the front of the hoist structure so that control cables 65 and 66 may be attached to the arms 61 and 62, respectively.

Control cables 65 and 66 attach to the front ends of pivotally mounted control levers 67 and 68, which levers may be adjustably carried on the hoist structure so as to be positioned at the unloading level of elevator platforms 14 and 15. Similar control cables 69 and 70 attach to the rear ends of control levers 67 and 68 and entrain under pulleys 71, whereby to extend forwardly to be attached to arms 64 and 63, respectively, of actuating device 60. This device 60 is attached to the upper end of shaft 55 carrying gear 54. Control levers 67 and 68 are arranged to project in the path of movement of elevator platforms 14 and 15 whereby, as either elevator platform ascends to its unloading level, the front end of the control lever engaged thereby will be moved upwardly, thereby pulling either control cable 65 or 66 with it, to rotate actuating device 60 about its mounting shaft 55. Such rotation of actuating device 60 rotates gear 54 and thereby rotates segment 53, which rotational movement is translated into a lineal movement by means of pin 50 and clutch yoke 51, to shift shaft 45. When gear 54 engages segment 53 midway, clutch element 38 is in neutral position. On the other

hand, when gear 54 is rotated in either direction to engage either end of segment 53, clutch element 36 is in engagement with either of clutch dogs 33 or 34 to drive drum 20.

Assume that elevator 14 is ascending to the unloading level. The front end of control lever 68 will be engaged by this elevator 14 and swung upwardly whereby to actuate control cable 66. This cable 66 fastening to arm 62 will rotate actuating device 60 and cause gear 54 to swing segment 53 to a neutral position shown in Fig. 2. The rotation of this segment shifts shaft 45 outwardly to throw clutch element 36 out of engagement with clutch dog 34. The driving mechanism is thereby disconnected from driving relation with drum 20 and elevator 14 will remain at its unloading level. If it is thereafter desired to raise platform 15 and allow platform 14 to descend, the rear end of control lever 67 is raised, which action actuates control cable 69 to move actuating device 60 counterclockwise. Segment 53 will be moved clockwise to shift clutch element 36 into engagement with clutch dog 33. Drum 20 is then rotated until elevator platform 15 engages the front end of control arm 67. Control cable 65 is thereby actuated to rotate actuating device 60 clockwise in order to return clutch element 36 to neutral position. Actuation of control cable 70 by the resetting of control lever 68 will rotate actuating device 60 and shift clutch element 36 into engagement with clutch dog 34.

Braking means may be employed to check the rotation of and hold the drum 20 against movement when the driving mechanism above described is in neutral position. Drum 20 is provided with an extension 79 furnishing a brake drum having a relatively large braking area for a brake band 80. A pair of springs 81 and 82 secured on opposite sides and between the ends of brake band 80 normally tend to apply the band against the brake drum. This action is overcome by means of a cam element 84 carried at the lower end of shaft 55 and acting to spread the ends of the brake band 80, when the driving mechanism is in driving engagement with drum 20. This cam element 84 is preferably rectangular in shape and lies between the ends of the brake band 80. When actuating device 60 is rotated, cam element 84 is turned whereby to apply the brake band 80 against the brake drum when the driving mechanism is in neutral position, and to release the brake band when the drive is connected to rotate drum 20. This braking means is very compact and effective, in view of its direct application of the braking power to the drum 20 and also in view of the maximum braking area which is obtained by positioning the brake on the drum.

Without further elaboration, the foregoing will so fully explain the gist of my inven-

tion, that others may, by applying current knowledge, readily adopt the same for use under varying conditions of service, without eliminating certain features, which may 5 properly be said to constitute the essential items of novelty involved, which items are intended to be defined and secured to me by the following claims.

I claim:

10 1. In a hoist of the type described, the combination with a plurality of elevator platforms adapted to be alternately raised and lowered, of mechanism for operating said elevator platforms comprising a pair of drive 15 gears, concentric sleeve members driven by said gears, clutch dogs carried by said sleeves, a clutch element adapted alternately to engage said dogs, a drum for winding thereon a cable leading to said elevator platforms, 20 the alternate engagement of said clutch element with said dogs producing alternate reverse rotation of said drum whereby said platforms are raised and lowered in proper sequence, a slidable shaft within said sleeves 25 for shifting said clutch element in either of its engageable positions with said dogs, and means controlled by the position of said elevator platforms for actuating said shaft.

2. In a hoist of the type described, the combination with elevator platforms, a suspensory cable therefor, a drum for actuating said cable, driving mechanism for said drum comprising oppositely rotating drive gears, concentrically arranged sleeves driven by 35 said gears and loosely carrying said drum, a pivotally mounted clutch element carried by said drum, clutch dogs operably associated with said sleeves, and a slidable shaft in the inner concentric sleeve for shifting said 40 clutch element into engagement with either of said clutch dogs.

3. In a hoist of the type described, the combination with elevator platforms, a suspensory cable therefor, drum means for actuating said cable, mechanism for alternately rotating said drum means in opposite directions comprising a pair of clutch dogs rotating in opposite directions, a clutch element pivotally carried adjacent said drum means 45 for alternately engaging said clutch dogs, and means controlled by the position of said elevator platforms for shifting said clutch element into engagement with either of said dogs.

55 4. In a hoist of the type described, the combination with elevator platforms, a suspensory cable therefor, drum means for actuating said cable, a pair of oppositely rotating shafts, a clutch dog for each shaft, 60 and a clutch element pivotally carried in driving relation on said drum means for alternately engaging said clutch dogs.

5. In a hoist of the type described, the combination with elevator platforms, a suspensory cable therefor, drum means for actuat-

ing said cable, a pair of oppositely rotating sleeves arranged in concentric relation, said drum being loosely mounted on one of said sleeves, a clutch dog for each sleeve, and a clutch element pivotally carried in driving 70 relation on said drum means for alternately engaging said clutch dogs.

6. In a hoist of the type described, the combination with elevator platforms, a suspensory cable therefor, drum means for actuating said cable, a pair of oppositely rotating sleeves arranged in concentric relation, said drum means being loosely mounted on one of said sleeves, a clutch dog for each sleeve, a clutch element pivotally carried in driving 75 relation on said drum means, and means slidably arranged within said sleeves for shifting said clutch element into alternate engagement with either of said clutch dogs.

7. In a hoist of the type described, the combination with elevator platforms, a suspensory cable therefor, drum means for actuating said cable, a drive for said drum means including reversing mechanism for reversing the rotation of said drum means, an actuating device for said reversing mechanism, said actuating device being rotatable to neutral and driving positions, tilttable control members at the unloading level engageable by 80 said elevator platforms, and control cables 85 attaching to each end of each control member and extending to said actuating device, the engagement of said control members at one end by said elevator platforms moving said actuating device to neutral position, the operation of said control members at their opposite ends moving said actuating device to 90 driving positions.

8. In a hoist of the type described, the combination with elevator platforms, a suspensory cable therefor, drum means for actuating said cable, driving means for alternately rotating said drum means including a shiftable clutch element, a pivoted segment, mechanism for translating the rotational 105 movement of said segment into lineal movement to actuate said shiftable clutch element, a gear in mesh with said segment, an actuating device for said gear, and control cables extending to said actuating device for 110 operating the same according to the position of said elevator platforms.

9. In a hoist of the type described, the combination with elevator platforms, a suspensory cable therefor, drum means for actuating said cable, mechanism for reversing the rotation of said drum means comprising a pair of oppositely rotating concentric sleeves, a clutch dog for each sleeve and a clutch element pivotally carried in driving relation on 120 said drum means for alternately engaging said clutch dogs, an actuating device for said reversing mechanism, said actuating device being rotatably mounted and movable by rotation to neutral and driving positions,

brake means for said drum, resilient means tending normally to apply said brake means, and means associated with said actuating device and operable by rotation thereof to release said brake means when said actuating device is moved to driving position.

10. In a hoist of the type described, the combination with elevator platforms, a suspensory cable therefor, drum means for actuating said cable, mechanism for reversing the rotation of said drum means comprising a pair of oppositely rotating concentric sleeves, a clutch dog for each sleeve and a clutch element pivotally carried in driving relation on said drum means for alternately engaging said clutch dogs, an actuating device for said reversing mechanism, said actuating device being rotatably mounted and movable by rotation to neutral and driving positions, a brake band for said drum means, resilient means tending to apply said brake band against said drum means, and a camming device operable by rotation of said actuating device for spreading said brake band.

In witness whereof, I have hereunto subscribed my name.

CARL ZETTERLUND.
